LUBRICATING COMPOSITION

Arnold J. Morway, Clark Township, Union County, and David W. Young, Roselle, N. J., assignors to Standard Oil Development Company, a corporation of Delaware

No Drawing. Application May 24, 1950,
Serial No. 164,034

5 Claims. (Cl. 252—42.1)

1

This invention relates to lubricating compositions and particularly to lubricating greases having outstanding oxidation resistance properties. More particularly this invention relates to a lubricating grease composition comprising a mineral base grease containing a small proportion of a bis-phenol sulfide as an oxidation inhibitor.

It is well known in the art of lubricating grease manufacture that the resistance of grease compositions to oxidation may be increased by adding to the grease composition small percentages of "oxidation inhibitors." Various oxidation inhibitors are well known in the art, examples being phenyl alpha naphthylamine, phenyl beta naphthylamine and other amine type compounds and intermediates and various of the alkylated phenols and phenol derivatives.

It has now been found that grease compositions containing minor amounts of bis(5-methyl-2-hydroxy phenyl) sulfide, referred to hereininafter simply as bis-phenol sulfide, have outstanding oxidation resistance properties.

The bis-phenol sulfide compound utilized in the grease compositions of this invention was prepared as follows:

109 g. of p-cresol was dissolved in 500 c. c. of petroleum ether. A solution of 55 g. of SCl_2 in 60 c. c. of petroleum ether was dropped in during one hour. The mixture was allowed to stand over night. The petroleum ether layer was then poured off from the brown semi-solid mass and the mass was crystallized from 100 g. of toluene. 27 g. of a white crystalline powder was obtained. Successive crystallizations from 100 c. c. of toluene and 100 c. c. of glacial acetic acid yielded odorless crystals of bis(5-methyl-2-hydroxy phenyl) sulfide, melting point 114° C. to 115° C.

Although it is preferred in this invention to incorporate the bis-phenol sulfide composition as an anti-oxidant, the metal salts of this compound may also be used either alone or in combination with the compounds themselves. The preferred embodiment of the invention contemplates incorporating the anti-oxidants into mineral oil base lubricating grease compositions although synthetic oil base greases, particularly those of the synthetic ester type oils, may be used.

The mineral oils used as a base for the lubricating compositions contemplated may be thickened to a grease consistency with any of the well known grease making soaps such as soaps of the alkali or alkaline earth metals. Especially desirable are the alkali metal soaps of unsaturated acids such as those contained in rape seed oil, lard oil, soya bean oil, cotton seed oil, fish oils,

etc. The alkali metal soaps of the saturated acids such as hydrogenated fish oil acids, stearic acid, hydroxy stearic acid, hydrogenated beef fat and tallow, or the glycerides of various fatty acids or mixtures of these in any proportion may be used.

Although the percentages of the anti-oxidant utilized in this invention may vary depending upon the use to which the grease composition is to be placed, an operable percentage range would be from 0.1% to 2.0% by weight of the anti-oxidant, preferably 0.5% to 1.5% by weight.

The grease compositions of this invention are prepared according to the following procedure:

- 15 The mineral lubricating oil is admixed with a preformed soap, or soap stock formed in situ in the mineral oil by saponification or neutralization of fats or acids respectively, in a grease kettle equipped for heating by either a steam jacket or 20 by a direct flame. The temperature of the mixture is raised with stirring to one in the neighborhood of 400 to 500° F. After the soap has become completely dispersed in the oil the heat is cut and the desired additives are added to 25 the molten grease, the mixing being continued during this addition. The resulting grease composition is then pan cooled or cooled in a continuous grease cooler according to standard procedures. If it is desired to formulate the soap in 30 situ, the desired amount of the saponifiable material is admixed with a portion of the mineral oil and the desired metal base, usually in the form of the hydroxide, is added. After complete saponification the balance of the mineral oil is 35 added and the temperature raised to the melting point of the soap. The desired anti-oxidant is added to the grease composition just before the grease is cooled.

- 36 The concept of this invention will be more 40 clearly explained by reference to the following: Various lubricating grease compositions were prepared according to the method outlined above in the following formulation:

- 45 63.03% mineral oil having a viscosity at 210° F. of 55 S. U.S.
29.00% of rape seed oil
5.29% of sodium hydroxide
1.0% of a mixture of equal parts of sodium sulfonate and a mineral oil
50 1.00% of the desired anti-oxidant

A metal deactivator of the chelate type may also be present if desired.

It is to be noted, of course, that varying 55 amounts of the percentages given may be used

in order to change the properties of the final grease composition. This variance is in accordance with techniques which are familiar in the art.

The experimental grease compositions of this invention were then subjected to the standard Norma-Hoffman oxidation bomb tests. The data on the compositions of this invention are reported in Table I below as hours necessary to obtain a certain pressure drop. As is well understood in the art, the greater the length of time necessary to obtain a certain pressure drop, the more stable a grease composition is to oxidation.

TABLE I
Norma-Hoffman oxidation tests on mineral oil experimental greases

Anti-Oxidant Used (1% by weight.)	Hours for Pressure Drop of—					
	5 p.s.i.	10 p.s.i.	15 p.s.i.	25 p.s.i.	55 p.s.i.	78 p.s.i.
None	46	52				96
I 2,6-di-tert-Butyl p-cresol	60	110	140	174		
II 2,6-di-phenyl ethyl p-cresol	46	50			180	
III Mixture of di- and tri-tert-octyl phenol		18	28	42	114	
IV Tert-octyl phenol alkylated with isobutylene		30		54	168	
V 2,2-bis(2-hydroxy-3-tert-Butyl-5-methylphenyl) propane	62	100	146			
VI 1,4-bis(3,4-dihydroxy benzene) 2,3 dimethyl butane	16	20	46	60	88	116
VII bis(5 methyl-2-hydroxy phenyl) sulfide	96	144	178	274		

It will be seen from the data reported in Table I that the bis-phenol sulfide composition of this invention has outstanding properties as an oxidation inhibitor, it requiring 96 hours to reach a 5 pound pressure drop and 274 hours to obtain a 25 pound pressure drop with a grease containing this inhibitor.

The phenolic type oxidation inhibitors are generally unstable in the presence of sunlight and form by-products which impart to grease compositions an undesirable darkening effect. Various samples of grease compositions containing different phenolic type inhibitors are compared, in Table II, with a grease sample containing the compound of this invention as to stability towards sunlight. It will be seen by an examination of the results given in Table II that whereas the other phenolic type inhibitors resulted in sample darkening after 60 days in sunlight, no change in the color of the grease was obtained when the bis-phenol sulfide was used as the oxidation inhibitor.

TABLE II
Light stability of experimental greases

Anti-Oxidant (1% by wt.)	Color Before Exposure to Sunlight	Color After 60 days Sunlight
None	clear	dark
I 2,6-di-tert-Butyl p-cresol	do	do
II 2,6-di-phenyl ethyl p-cresol	do	do
III Mixture of di- and tri-tert-octyl phenol	do	do
IV tert-octyl phenol alkylated with isobutylene	do	do
V 2,2-bis(2-hydroxy-3-tert-Butyl-5-methylphenyl) propane	do	do
VI 1,4-bis(3,4-dihydroxy benzene) 2,3 dimethyl butane	do	do
VII bis(5 methyl-2-hydroxy phenyl) sulfide	do	no change

The bis-phenol sulfide utilized in this invention as an oxidation inhibitor is perfectly compatible with other additive materials familiar in the art of grease manufacture.

5 What is claimed is:

1. A lubricating grease composition consisting essentially of a lubricating oil thickened to a grease consistency with a metal soap of a fatty acid having combined therein a minor but oxidation resistance improving amount of bis(5-methyl-2-hydroxy phenyl) sulfide.
- 10 2. A lubricating grease composition consisting essentially of a mineral lubricating oil thickened
